(57) CLAIM

The ornamental design for a front grille for automobile, as shown and described.

DESCRIPTION

FIG. 1 is a front perspective view of a front grille for automobile, showing my new design.

FIG. 2 is a front elevation view thereof.

FIG. 3 is a top plan view thereof.

FIG. 4 is a bottom plan view thereof.

FIG. 5 is a left side elevation view thereof; and,
FIG. 6 is a right side elevation view thereof.

The claim is shown in full-tone shading. Neither elements shown in half-tone shading nor the broken lines themselves form any part of the claimed design.

1 Claim, 6 Drawing Sheets
